UNITED STATES PATENT OFFICE

PAUL G. SWARS, OF PITTSBURGH, PENNSYLVANIA

ELECTRICAL CONTACTING DEVICE

Application filed November 12, 1928. Serial No. 318,886.

My invention relates to electrical contacting devices, and more particularly to electrical contacting devices having provision for insuring adequate pressure between current conducting members.

In transferring electrical energy between current conducting members, the efficiency of the contact depends in part upon the areas of engagement between the conducting parts, and upon the pressure exerted between the parts. Where uneven contact exists between the different portions of engaging current conducting members, there is an uneven distribution of current about the contacting faces. The unequal distribution of current causes localized heated spots. Where spaces exist between the contacting surfaces, the electrical resistance of the connection is increased with a resultant increase of heating.

10 In some cases the localized heating has been sufficiently great to ruin the temper of the electrical conducting material and adjacent reinforcing members.

The current conducting materials most commonly used are copper and aluminum. Both of these materials are relatively soft and do not possess sufficient resistance to bending forces to enable them to keep their shapes and thereby preserve good contacting surfaces. This is especially true after the current conducting members have once been subjected to heavy electrical currents which are liable to anneal the current conducting members. For reinforcing the current conducting members and supplying sufficient pressure to insure good electrical contact between current conducting surfaces, reinforcing or bracing strips have been applied along the surfaces of the current conducting members opposite their current transferring surfaces. Such reinforcing members are often mounted on the same base as the current conducting members and are frequently in parallel circuit to one or more of the current conducting members.

Reinforcing members, when in parallel circuit with the current conducting members, are liable to conduct a considerable amount of current unless provision is made for increasing the electrical resistance of the cur-

rent path through such reinforcing members. Under normal loads, the current traversing the reinforcing members may not be excessive, but under conditions of short-circuit or current surge, where the current is greatly increased, there is danger of the reinforcing members being excessively heated and annealed at a time when full contact pressure is most needed. For increasing the resistance of the electrical path through reinforcing members, it has heretofore been proposed to insert sheets of electrical insulating material between each current conducting member and cooperating reinforcing member.

The presence of sheets of fabricated insulating material in electrical contacting devices virtually necessitates that the contacting device shall be used in-doors in comparatively dry places. Most fabricated insulating materials deteriorate rapidly when exposed to the actions of gases and fumes such as are present in the atmosphere in most industrial communities. Such material cannot be used when continuously exposed to moist atmosphere such as is present around large bodies of water, or in many industrial plants, as the insulating material tends to absorb water and become a conductor. It has been repeatedly demonstrated that the best non-conducting heat dissipators for exposed work are air and inert gases. For enclosed work the best non-conducting heat dissipators are high-fire test oils or non-conducting liquids, such as carbon tetrachloride. Where a body of any of the foregoing non-conducting heat dissipators can be positioned between portions of a current-carrying member and a reinforcing member, the presence of the body of non-conducting heat dissipator tends to reduce the amount of current traversing the reinforcing members.

I provide a reinforcing or tensioning means for electrical contacts in which a metallic reinforcing member directly engages a current conducting member. The metallic reinforcing member is shaped to provide a large volume of a non-conducting and heat-dissipating medium between its surface and the surface of the current conducting member, while maintaining a well distributed and firm

pressure. By providing a plurality of spaced projections or lugs distributed over a relatively large surface and engaging the current conducting member, the body of the reinforcing member is spaced from the body of 5 the current conducting member.

The space is filled with a non-conducting medium, which is permitted to circulate between the surface of the reinforcing member 10 and the electrical conducting member, thereby dissipating such heat as is developed.

In order to increase the electrical resistance of a current conducting path through the reinforcing member, the projections are made of 15 relatively small cross-sectional areas near their points of contact with the current conducting member. In case excessive current tends to traverse the projections, they become heated at their points of contact. However, 20 by reason of the limited cross-sectional areas of the projections, they offer considerable electrical resistance, which resistance increases as their temperature increases. Accordingly, the heated portions of the projections 25 are limited for short distances from their outer ends. As an insulating medium is continuously circulating past the projections, the heat is quickly dissipated and the body of the reinforcing member is kept at a temperature 30 to prevent its becoming annealed.

The accompanying drawing illustrates certain present preferred embodiments of the invention in which

Figure 1 is an elevational view of an electrical clip and cooperating knife blade involving my invention;

Fig. 2 is a similar view showing a modified form of clip;

Fig. 3 is a similar view showing a modified 40 form of the invention adapted for use with circular conducting members;

Fig. 4 is a diagrammatic view of a form of the invention adapted for use with drum contacts;

Fig. 5 is a view illustrating a brush and brush-holder provided with my invention;

Figs. 6, 7 and 8 illustrate different forms of reinforcing members, and

Fig. 9 is a perspective view of a further 50 modification of the invention.

Referring to Fig. 1, an electrical clip 2 is provided with a base 4 from which stationary contacting jaws 5 extend. The jaws 5 are copper and extend in parallelism from 55 the base 4. The jaws 5 are spaced apart far enough to permit the entrance of a blade 6 of current conducting material, such as copper. The blade 6 is illustrative of a knife in a knife blade switch, or the end of a fuse having 60 a flat current conducting extension.

In order to provide a uniform engagement between the jaws 5 and the blade 6, reinforcing or tensioning members 7 in the form of metallic springs, preferably of ferrous metal, 65 are secured to the base 4 by screws 8. It is to

be understood that other forms of securing means may be substituted for the screws 8 if desired. The reinforcing members 7 are provided with a plurality of projections 9 along their inner faces.

It is to be understood that the projections on the reinforcing members may be formed by a punch operation, riveting, screw fitting, welding, and the like.

The presence of the projections 9 between 75 the reinforcing members 7 and the jaws 5 provides spaces through which an insulating medium such as air, an inert gas, or a non-conductive liquid, such as oil or carbon tetrachloride, may circulate. The circulation of 80 the insulating medium dissipates the heat developed during the operation of the contact, thereby preventing the reinforcing members from becoming excessively heated and annealed.

The projections 9 are of relatively small 85 cross-sectional area at their outer ends. The number of the projections is such that a firm and uniformly distributed pressure is transmitted from each reinforcing member 7 to 90 its cooperating jaw 5. However, the cross-sectional areas of the ribs are so small that each rib offers a considerable resistance to the passage of electrical current. Should an excessive amount of current tend to traverse 95 the projections 9, they become heated, which increases their resistance to the transmission of current. Due to their small cross-sectional areas, the circulating medium rapidly dissipates such heat as is developed. The presence 100 of the heated portions at the ends of the projections does not impair the reinforcing and tensioning characteristics of the members 7.

As illustrated in Figs. 6, 7 and 8, the projections 9 may be any one of several forms.

In Fig. 6 projections 9a of small cone-like shape are struck up from the body of the reinforcing member. In Fig. 7 elongated projections 9b are struck up from the body of a reinforcing member 7a. The projections 9b 110 are arranged to extend radially from a common center.

Referring to Fig. 8, a metallic screen 10 is secured between a conductor and a reinforcing member 7c. The screen may be secured to 115 the reinforcing member in any desired manner, as by spot welding. The screen may be welded to the conductor if desired.

Referring to Fig. 2, the invention is applicable to a contact device having a single stationary contact member 11 mounted on a base 12. A second current conducting member 13 bears against the inner edge of the stationary contact member 11. A resilient member 14 having projections 15 formed thereon 125 bears against the second surface of the conducting member 13.

Referring to Fig. 3, the invention is applicable to circular conducting members 16 such as the ends of fuse clips, by providing the 130

customary curved clips 17 with curved reinforcing members 18 secured to a common base 20 for the clips 17. The reinforcing members 18 are provided with projections 19 corresponding to the projections 9 shown in Fig. 1.

5 Referring to Fig. 4, the invention is applicable to drum type contacting devices. A current conducting drum 21 is mounted in supports 22.

10 A contacting finger 24 engages a portion of the surface of the drum 21. A reinforcing member 25 bears against the outer face of the finger 24. The inner surface of the reinforcing member 25 is provided with projections 26 which engage the outer surface of the finger 24. The projections 26 perform the same functions as the projections 9 shown in Fig. 1.

15 20 Referring to Fig. 5, the invention is applicable to brushholders. A brushholder 27 encloses a brush 28 against the outer end of which a reinforcing member 29 bears. Projections 30 on the inner surface of the reinforcing member 29 engage the outer end of the brush 28.

25 30 In Figure 9 I have shown a modification of the invention, in which clips 17a, corresponding to the clips 17 shown in Figure 3, are provided with projections 19a which engage the surface of a reinforcing member 18a having substantially a plain surface.

35 While I have shown and described certain present preferred embodiments of the invention, it is to be understood that the invention may be otherwise embodied within the spirit of the invention and the scope of the appended claims.

I claim:

1. In a switch, the combination with a movable blade, and jaws adapted to frictionally engage said blade when in closed position, of leaf springs for urging said jaws into engagement with said blade, having high electrical resistance and a plurality of sharp points engaging said jaws.

2. The combination with a contact member adapted to frictionally engage a conductor, of a reinforcing member for urging the contact member into firm engagement with the conductor, and spaced projections on one of said members for transmitting the effect of the reinforcing member to the contact member.

55 55 In testimony whereof I have hereunto set my hand.

PAUL G. SWARS.
